CLAIM

The ornamental design for an electrical power unit for a work surface, as shown and described.

DESCRIPTION

FIG. 1 is a top perspective view of an electrical power unit for a work surface showing our new design;

FIG. 2 is another top perspective view of the electrical power unit of FIG. 1, shown with its fastening collar engaged;

FIG. 3 is a top plan view of the electrical power unit of FIG. 2;

FIG. 4 is a bottom plan view of the electrical power unit of FIG. 2;

FIG. 5 is a right side elevation of the electrical power unit of FIG. 2;

FIG. 6 is a left side elevation of the electrical power unit of FIG. 2;

FIG. 7 is a front elevation of the electrical power unit of FIG. 2; and,

FIG. 8 is a rear elevation of the electrical power unit of FIG. 2.

In the drawings, the broken lines depict environmental subject matter only and form no part of the claimed design.
